INVENTOR.

Tom L. Johnson,
C. Bradford,
ATTORNEY.

UNITED STATES PATENT OFFICE.

TOM L. JOHNSON, OF INDIANAPOLIS, INDIANA.

CURVE, FROG, &c., FOR STREET-RAILROADS.

SPECIFICATION forming part of Letters Patent No. 276,419, dated April 24, 1883.

Application filed October 31, 1882. (No model.)

To all whom it may concern:

Be it known that I, TOM L. JOHNSON, of the city of Indianapolis, county of Marion, and State of Indiana, have invented certain new and useful Improvements in Curves, Frogs, &c., for Street-Railroads, of which the following is a specification.

The object of my said invention is to produce forms of curves, frogs, crossings, &c., suitable to be used with the combined tram and T rail which is coming into use on street-railroads, which can be conveniently cast by the ordinary method of molding. This object is accomplished by the construction of such parts hereinafter more particularly described and claimed.

Referring to the accompanying drawings, which are made a part hereof, and on which similar letters of reference indicate similar parts, Figure 1 is a plan view of a portion of a street-railroad, embracing a switch, frog, and curve, with the construction incident to the several parts employed; Fig. 2, a side elevation of the ends of two track portions (one rolled and one cast) and the splice-bar connecting them; Fig. 3, an under side plan of a portion of a cast track part; Fig. 4, a perspective view of one end of one of the curved portions; Fig. 5, an end elevation of the frog D as seen from the dotted line z z; Fig. 6, an end elevation of the switch E as seen from the dotted line y y; Fig. 7, a transverse section of the crossing-frog F, looking toward the center from the dotted line x x; Fig. 8, a section of said frog, looking toward the center from the dotted line w w; Fig. 9, an end elevation of the outer curve-rail, B; Fig. 10, a transverse section of the same on the dotted line v v; Fig. 11, an end elevation of the inner curve-rail, C; Fig. 12, a transverse section of the same on the dotted line u u; Fig. 13, an end elevation of the rolled-iron rail which I use in the straight portion of the track, and which is adapted to be connected by splice-bars in the ordinary manner to any of the other parts; and Fig. 14, a horizontal section through a joint between a rolled and cast portion on the dotted line t t.

In said drawings, the portions marked A represent the combined tram and T rail which I use in the straight portion of the track; B, the cast outer curve-rail; C, the cast inner

curve-rail; D, the frog; E, the switch, and F the crossing-frog.

The flanges *a* are common to all the parts, (rolled as well as cast;) but in the cast-metal parts they are preferably only present for a small portion of the length thereof. In some constructions, where there are two webs in a single part, said flanges *a* are only cast upon one side of each web, as shown in Figs. 5 and 6. The webs of the several parts are also substantially alike, except that those of the cast-metal portions are usually somewhat thicker than those of the rolled rails, as cast-metal webs no thicker than the rolled webs are intended to be, especially when unprovided with flanges, as shown, would be too subject to fracture, and parts having such webs would therefore be of uncertain durability. By reason of the differing thicknesses of the webs one or both of the splice-bars *a'* *a''*, which connect rolled and cast parts together, should be bent or have "offsets" therein in order to hold the parts properly. This is illustrated in Fig. 14, where the webs are shown so arranged that the bend or offset is in one of the splice-bars only.

The several cast-metal parts are grooved and flanged at the top, as shown in Figs. 4 to 12, in order to prevent the wheels of the cars from running off the track while said cars are passing over the frogs or switches or around the curves.

As is well known by persons skilled in the art, a casting of the form of any of the parts B C D E F would be very difficult to mold properly were the flanges *a* cast thereon for the whole length thereof. The use of large and unwieldy cores is the only means by which it can be done, and cores of the size and shape necessary for this purpose are difficult to make, and difficult to use without breaking when made.

By experiments I have found that the flanges *a* can be dispensed with, except at the extreme ends of the parts described, without seriously impairing the serviceableness or strength of said parts; and it will be readily seen by an examination of the form of the cross-sections of said parts that they can then be cast without the use of cores, except at said ends, without trouble. For the short portions on which

flanges are necessary they are formed by the use of cores; but such cores, being comparatively very short, are easily and safely handled, and do not add materially to the trouble or expense of the manufacture. Track portions formed in this manner possess all the desirable features of any devices of the character and for the purposes, while the cost is much less than any other which are as serviceable.

Having thus fully described my said invention, what I claim as new, and desire to secure by Letters Patent, is—

1. The combination, in a street-railroad composed of combined tram and T rails, with said rails, of cast-metal frogs, curves, &c., said cast-metal parts being severally provided with webs

corresponding to the webs of the rolled rails for their whole length, and with flanges at the ends where said rails meet said cast-metal parts, or said parts each other, substantially as set forth.

2. A curve-rail provided with grooves, web, and flanges, as specified, whereby said curve-rail is adapted for use with a combined tram and T rail in the construction of street-railroads, substantially as set forth.

In witness whereof I have hereunto set my hand and seal, at Indianapolis, Indiana, this 25th day of October, A. D. 1882.

TOM L. JOHNSON. [L. S.]

In presence of—

C. BRADFORD,
E. W. BRADFORD.
